UNITED STATES PATENT OFFICE.

EDWARD CARL MUELLER, OF WEST ALLIS, WISCONSIN, ASSIGNOR TO STERLING WHEELBARROW COMPANY, OF WEST ALLIS, WISCONSIN, A CORPORATION OF WISCONSIN.

RADIAL DRILL PRESS.

Application filed October 27, 1919. Serial No. 333,526.

To all whom it may concern:

Be it known that I, EDWARD CARL MUELLER, a citizen of the United States, and resident of West Allis, in the county of Milwaukee and State of Wisconsin, have invented new and useful Improvements in Radial Drill Presses, of which the following is a description, reference being had to the accompanying drawings, which are a part of this specification.

The present invention relates to certain new and useful improvements in radial drill presses and has for one of its objects to provide a drill feed lever or mechanism capable of feeding the drill spindle longitudinally and being so mounted that it may be swung in a plane at right angles to the direction of longitudinal movement of the spindle, whereby the same may be adapted for convenient working on work of various sizes and shapes.

Another object of the present invention is to provide a vertically reciprocal sleeve member in which the drill shaft is journalledly mounted and having counter-balanced means connected therewith and carried by one section of the over-hung boom or beam whereby said sleeve member will be at all times urged to its upper limit of movement whereby a drill carried by the drill shaft will be in inoperative position.

A further object of the present invention is to provide a radial drill press having what may be termed a double-jointed overhung boom or beam whereby the overhanging boom may be readily positioned to conveniently work on work of various sizes and shapes.

A still further object of the present invention is to provide a two-part pivotally connected together overhung boom having the drive motor for the drill shaft mounted at the pivot of the two-parts of said boom or beam.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings I have illustrated one complete example of the physical embodiment of my invention constructed according to the best mode I have so far devised for the practical application of the principles thereof, and in which:

Fig. 1 is a side elevational view of an over-hung boom or beam constructed according to and embodying the various features of my invention, the supporting standard or post being only partially shown.

Fig. 2 is a view part in section and part in elevation illustrating the outer end of the outer arm or member of the over-hung boom or beam, depicting the manner of journalling the drill shaft within the sleeve member and the sleeve member within the feed handle carrying collar.

Fig. 3 is a detailed sectional view taken on the line 3—3 of Fig. 2, and

Fig. 4 is a detailed sectional view taken on the line 4—4 of Fig. 2.

Referring now more particularly to the accompanying drawing, the numeral 5 designates a vertical supporting standard or post of a drill press which is preferably mounted adjacent a work supporting base or table (not shown) and has mounted on its upper end a shaft 6 to which is swingingly secured the outer end 7 of an arm 8 of the novel form of double jointed or swingingly connected together two-part over-hung boom member to be described.

In the drawings I have illustrated the over-hung boom member being pivotally but not adjustably secured to the standard 5, but it will be understood that the end 7 of the section 8 of the over-hung boom member is swingingly as well as vertically adjustably secured to the standard 5 as is customary in the radial drill presses now in common use. As this feature has no important bearing upon the present invention, in that it is old and well-known in the art, a non-adjustable swinging connection between the standard 5 and the over-hung boom is shown in the drawings, although I wish it understood that I do not consider myself as restricted to the showing with reference to this feature.

The inner end 9 of the arm 8 has formed therein two-cup shaped bearing members 10 for receiving a suitable ball bearing (not shown) for engaging the pivot shaft 11

mounted therein and having its ends fixed in the spaced apart bearing members 12 formed on the inner end 13 of the outermost arm 14 of the over-hung boom or beam. The 5 arm member 8 is substantially reenforced by a central longitudinally extending medial brace 15 which connects the ends 7 and 9 thereof, and the arm 14 is braced by a series of substantial transverse ribs or partitions 10 16 connecting the sides of the arm 14. The outer end of the arm 14 is formed with a pair of spaced apart bearings 17 and 18, and in the bearing 18 is journaled one end of a driven drill carrying shaft 19, and in 15 the bearing 17 is slidably and rotatably journaled one end of a sleeve member 20, to be later described.

The shaft 19 is provided with two spaced apart enlargements 21 which are journally 20 mounted in the end bearing portions 22 of the sleeve member. As before described, the sleeve member 20 is slidably and rotatably journaled in the bearing 17, and I provide novel means for moving the sleeve member 20 vertically to feed the shaft 19 downwardly with its drill (not shown) 25 adapted to be carried in the socket member 23 formed on the lower end of the shaft 19. As best shown in Figures 1 and 3, the sleeve member 20 has formed in one side thereof a toothed rack 24 in mesh with a gear wheel 25 journally mounted in a collar member 26 in which the member 20 is slidably mounted. The lower end of the collar 26 is journaled 30 in the bearing 17 and serves as a bushing between the sleeve 20 and the bearing 17. The shaft 27 to which the gear 25 is secured by a binding nut 28 has mounted on one end a disk member 29 in which is removably 35 mounted a feed handle 30. As best shown in Figures 2 and 3, the member 29 has a plurality of openings 31 therein, whereby the adjustment of the handle 20 is accomplished.

40 By reason of the engagement of the rack 24 with the gear 25, when the collar member 26 is rotated by means of the handle 18, the sleeve member 20 must necessarily revolve in its bearing 17, and in this manner the handle 30 may be positioned in any desired 45 manner for convenience in drilling. In the presses now in common use, the drill feeding handle is not capable of rotation, and thus often times considerable inconvenience 50 is experienced in drilling definite kinds of work, whereas, with my construction, the collar member 26 is free to rotate and can be positioned to suit the class of work being drilled.

55 The upper end of the shaft 19 has formed therein a longitudinally extending key-way 32 whereby the shaft is non-rotatably, but vertically movably secured in the central bore of a beveled gear 33 journally carried 60 by the bearing 18. This construction per-

mits the shaft 19 to be moved vertically and still, at all times, be in drive connection with the gear 33. The beveled gear 33 is in mesh with a beveled pinion and drive shaft 35 connected with a driving motor 36 mounted 70 upon the top base 37 formed on the top-most bearing member 12 of the arm 14. This construction permits the swinging of the arms 8 and 14 on their pivot 11 without interrupting the drive connection between the 75 motor and the shaft 19. The gears 33 and 34 are protected by a suitable housing 38.

A collar member 39 is rotatably mounted upon the upper end of the sleeve member 20 and is provided with a pair of opposed trunnions 40 which are pivotally engaged by the outer forked end 41 of a lever 42. The lever 42 is pivotally suspended from the arm 14 by means of a link member 43 pivoted to the upper portion of the arm, 80 as at 44, and to the lever medially of its ends, as at 45. The inner end of the lever 42 is pivotally connected with a counterbalanced weight being slidably mounted between the innermost pair of braces 16. 85 The lever 42 passes through aligned guide ways formed by breaking the outermost brace members 16 and connecting the break together by means of plates 48 secured on each side thereof to provide a slot therebetween. The innermost plates 48 are of less width than the adjacent brace members 16 to provide a small recess 49 for convenience in removing the counter-balance weight 46. By this structure, it will be readily seen 90 that when pressure is released from the handle 30, the counter-balance 46 will immediately raise the shaft 19 and consequently remove the drill from the work. The shaft 19 is held in the sleeve member 20 by means 95 of a ball thrust bearing 50 engaged between the shoulder 51 formed by the socket member 23 and the adjacent lower end of the sleeve member 20 and by suitable lock nuts 52 threaded on the upper enlargement 21 of 100 the shaft 19.

From the foregoing description taken in connection with the accompanying drawing, it will be readily apparent to those skilled in the art to which an invention of this character appertains, that I have provided a radial drill press which will be practical for the purposes described.

What I claim as my invention is:

1. In a drilling machine, the combination 120 of a spindle mounted for rotative and longitudinal movement, and means for feeding the spindle longitudinally, said feeding means being mounted to swing in a plane at right angles to the direction of the longitudinal movement of the spindle.

2. In a drilling machine, the combination 125 of a bearing, a sleeve journaled in and movable axially with respect to said bearing, a spindle journaled in said sleeve, means to 130

- drive said spindle, and means associated with said bearing and swingable in a plane at right angles to the axis of said spindle, said means being adapted to effect axial movement of said sleeve in said bearing. 5
3. In a drilling machine, the combination of a bearing, a sleeve journaled in and movable axially with respect to said bearing, a spindle journaled in said sleeve, means to 10 drive said spindle, a collar surrounding said sleeve and journaled in said bearing, and means carried by said collar for effecting axial movement of said sleeve in said bearing.
- 15 4. In a drilling machine, the combination of a bearing, a sleeve journaled in and movable axially with respect to said bearing, a spindle journaled in said sleeve, means to drive said spindle, a collar surrounding said 20 sleeve and journaled in said bearing, a transversely extending shaft journaled in said collar, and means connecting said shaft and sleeve for effecting axial movement of said sleeve in said bearing.
- 25 5. In a drilling machine, the combination of a bearing, a sleeve journaled in and movable axially with respect to said bearing, a spindle journaled in said sleeve, means to drive said spindle, a collar surrounding said 30 sleeve and journaled in said bearing, a transversely extending shaft journaled in said collar, an operating member associated with said shaft, said sleeve having a longitudinally extending rack, and a pinion on said shaft in mesh with said rack, for the purpose 35 specified.
6. In a drilling machine, the combination of a bearing, a vertically extending sleeve journaled in and movable axially with respect to said bearing, a spindle journaled in said sleeve, means to drive said spindle, means associated with said bearing and swingable in a plane at right angles to the axis of said spindle for effecting movement of said sleeve in one direction in said bearing, and counter-balancing means for effecting movement of said sleeve in said bearing in the opposite direction. 40
7. In a drilling machine, the combination of a bearing, a sleeve journaled in and movable axially with respect to said bearing, a spindle journaled in said sleeve, a gear slidably but non-rotatably mounted on said spindle, power means associated with said gear, and means associated with said bearing and swingable in a plane at right angles to the axis of said spindle for effecting axial movement of said sleeve in said bearing. 45
